UNITED STATES PATENT OFFICE.

EDWARD W. ISOM, OF SCARSDALE, NEW YORK, AND ARNOLD CHARLES VOBACH, OF WHITING, INDIANA, ASSIGNEES TO SINCLAIR REFINING COMPANY, OF CHICAGO, ILLINOIS, A CORPORATION OF MAINE.

OIL STILL.

Application filed February 12, 1927. Serial No. 167,680.

This invention relates to improvements in oil stills such as are commonly used in the distillation of hydrocarbon oils under pressure for the production of lighter hydrocarbon oils therefrom. More particularly, this invention relates to improvements in circulatory oil cracking stills in which the main body of oil is maintained at a cracking temperature in a bulk supply tank by circulating the oil from and to the bulk supply tank through a battery of heating tubes arranged in a suitable heating furnace.

In the operation of the apparatus of the invention intimate contact is secured between the oil being treated and the heat transferring surfaces. The length of travel of the circulating oil in contact with the heating surfaces in a still of given dimensions is also increased and the tendency toward local overheating with the consequent formation of heat insulating carbon deposits on the heat transferring surfaces greatly reduced, thereby increasing the capacity of the still and the efficiency of the operation.

The invention is of particular application in connection with oil cracking stills of the general character shown in Patent No. 1,285,200 granted to the Sinclair Refining Company on the application of E. W. Isom, November 19, 1918.

The cracking of heavier hydrocarbon oils by distillation under pressure for the production of lighter hydrocarbon oils therefrom is accompanied by the formation of fixed gas and carbon, pitch, etc., the character and amount of which are functions of the temperature, the amount increasing rapidly as the temperature necessary to effect the desired cracking is exceeded. The carbon formed tends to adhere to the heated surfaces of the still insulating them from the cooling effect of the circulating oil. This action is cumulative and may cause extremely high temperatures to be reached in a comparatively short time which impairs the strength of the material and sometimes causes rupture of the still or tube walls, but in any event necessitates shutting down the still for cleaning.

According to the present invention the heating tubes are provided with cores centrally located therein and extending entirely through the heated portions thereof. These cores are in the form of twisted rods so as

to present an extended surface of generally 55 helical configuration. In stills of the type particularly referred to circulation of the oil through the bank of heating tubes from and to the bulk supply tank is maintained by some suitable forcing means such as a pump 60 arranged in the circulating connections. By providing twisted cores in the heating tubes in accordance with the present invention the velocity of circulation is materially increased due to the decrease in cross sectional area of 65 the heating tubes and the correspondingly greater ratio of heating surface to volume. The helical configuration of the cores tends to cause the annular streams of circulating oil surrounding them to assume helical paths 70 of increased length, any centrifugal action assisting in preventing the accumulation of carbonaceous material on the heated tube walls and assuring intimate contact of the circulating oil therewith. The increased rate 75 of heat transfer, due to the greater velocity of flow, and the greater length of travel in contact with the heat transmitting surfaces are both effective in increasing the capacity and efficiency of the operation while the 80 greater protection against local overheating of, and carbon deposition on, the heated tube walls permits a longer operating time to be obtained between shutdowns for cleaning and repairs.

The invention will be further described in connection with the accompanying drawings illustrating in a somewhat conventional and diagrammatic manner one embodiment of the apparatus of the invention, but it is intended and will be understood that the invention is illustrated thereby, but is not limited thereto.

In the drawings:

Fig. 1 is an elevation partly in section of 95 a pressure still embodying the invention;

Fig. 2 is a sectional elevation, to an enlarged scale, of a portion of the battery of heating tubes and the upper header.

The pressure still illustrated in Fig. 1 is 100 of the general character described and illustrated in Patent No. 1,285,200, previously referred to. It comprises a bulk supply drum 1, adapted to maintain the main body of oil being cracked, a vapor line 2 for the escape 105 of vapors of the cracked oil, a battery of heating tubes 3 arranged in a furnace, a circulating pump 4 and circulating connections

5, 6 and 7 connecting successively the bulk supply drum, the circulating pump, the lower end of the heating tubes, the upper end of the heating tubes and the bulk supply drum. The vapors escaping from the bulk supply drum to the vapor line 2 may be passed through the reflux tower 8 in which they may be subjected to direct contact with fresh oil charged to the still. The vapors from the reflux tower escape through vapor line 9 to a condenser 10, and receiver 11 from which the distillate and uncondensed vapors and gases may be separately withdrawn. Reflux and admixed fresh oil when fresh oil is introduced into the reflux tower, are returned to the still through connection 12. Fresh oil may be introduced to the upper end of the reflux tower through connection 13. Cool fresh oil may be supplied to the bearings of the circulating pump through connection 14 to cool and protect the same. A connection 15 is provided for pumping out and initially charging the still. A connection 16 is arranged for withdrawing tar from the still during the operation thereof.

The furnace structure comprises a firebox 17 which may be of any usual or approved construction furnishing the required amount of heat, an uptake 18, and a downtake heating flue 19 connecting with the stack 20. The battery of oil heating tubes 3 is suspended vertically in the heating flue 19, the upper header 21 thereof being supported on I-beams 22 and 23 on top of the furnace. The heated products of combustion descending the heating flue 19 are caused to circulate back and forth over the heating tubes by means of the baffles 24 and 25. The lower end of the heating flue is closed by a partition or floor 26 arranged somewhat above the lower end of the heating tubes and supported thereby. The upper end of the heating flue is closed by partition 27 arranged in the opening in the top of the furnace through which the heating tubes depend, this partition as well as the baffles 24 and 25 being supported by the heating tubes. The heating tubes 3 of the battery are thus suspended from their upper end and may expand or contract freely with change of temperature. The battery of heating tubes may likewise be removed as a unit through the opening at the top of the furnace for the purpose of inspection and repair. The front tubes in the battery of heating tubes are prevented from receiving an undue amount of heat by direct radiation from the firebox 17 by provision of the bridge wall 28 and the elongated flue or uptake 18, the bridge wall acting as a screen to cut off direct radiation from the firebox to the heating tubes.

The heating tubes 3 are provided with twisted cores 29 suitably supported therein and extending centrally therethrough. One particularly advantageous type of core con-

struction is shown in detail in Fig. 2. In the arrangement there shown the cores 29 are made from rods of somewhat greater length than the tubes in which they are arranged and of some standard shape such as standard triangular, square, rectangular or hexagon bars. The upper ends of the rods are bent to form hooks by which the cores may be suspended, but which are of such breadth that they may be readily withdrawn through the openings in the headers arranged to register with the ends of the heating tubes and closed by the removable plugs 30. That portion of the rods below the suspending hooks is twisted, the edges of the rods forming helical ridges on their surfaces.

The heating tubes are thus provided with helical cores centrally arranged therein and extending therethrough which may be readily removed to facilitate cleaning, but which are nevertheless of exceptionally simple and cheap though rugged construction.

In the operation of the apparatus of the invention oil is circulated from the bulk supply drum 1 by means of the circulating pump 4 to the lower end of the heating tubes 3 and thence upwardly therethrough in relatively thin annular streams in intimate contact with the tube walls and back to the bulk supply drum. Circulation is assisted by the progressive heating of the oil and the tube walls are swept clean by the scrubbing action of the circulating oil flowing thereover. The hot products of combustion arising from the firebox are first contacted with the upper end of the heating tubes and are then caused to circulate back and forth over the heating tubes downwardly to the connection with the stack flue 20, the flow of heating gases over the heating tubes being generally countercurrent to the flow of circulating oil therethrough.

We claim:

In tubular oil cracking pressure stills, a bulk supply drum, a battery of heating tubes connected in multiple, and means for circulating heating gases thereover, connections between the bulk supply drum and the battery of heating tubes including a forcing means whereby oil may be circulated from and to the bulk supply drum through the battery of heating tubes in a direction generally countercurrent to the flow of heating gases thereover, the upper ends of the battery of heating tubes being below the usual liquid level in the bulk supply drum, said heating tubes having stationary solid cores formed of twisted rods arranged in and extending centrally therethrough, leaving a continuous annular oil passage through said heating tubes.

EDWARD W. ISOM.
ARNOLD CHARLES VOBACH.
